SPOOL

Arthur J. Weiss, West Englewood, N. J., assignor
to Robert Gair Company, Inc., New York, N. Y.,
a corporation of Delaware

Application January 30, 1947, Serial No. 725,398

10 Claims. (Cl. 242—119)

1

The invention relates to spools such as used for holding tape, cord, wire, etc.

The spools ordinarily employed are made by tacking pieces of paperboard to the ends of sticks of wood, the sticks comprising the body of the spool over which the material is to be wound and the paperboard comprising the ends or flanges of the spool. Empty spools of this type are cumbersome to pack for shipment and take up considerable space.

It has been an object of my invention to provide a folding spool which can be made from a single piece of paperboard without the use of wood sticks.

Another object of my invention is to provide a spool which can be shipped flat and which is simple to set up for use.

Other objects and advantages of my invention will appear as the description proceeds.

In the drawings, Fig. 1 is a face view of a blank for forming a spool or reel embodying my invention in its preferred form.

Fig. 2 is a view of the upper part of the spool as formed from the blank of Fig. 1 by folding over and stapling the end pieces thereof, the spool being in the flat or "knocked down" condition, i. e. before it has been set up into finished spool form for use.

Fig. 3 is a top view of the completed spool as set up for use; and Fig. 4 is a transverse sectional view taken as indicated at 4—4 in Fig. 3.

Figs. 5 and 6 are detail sectional views taken as indicated at 5—5 and 6—6 respectively in Fig. 4.

Figs. 7 to 13 inclusive illustrate a modified construction, Fig. 7 being a face view of the blank, and Fig. 8 a view of the upper part of the spool as formed from the blank of Fig. 7 by folding over and gluing the end pieces thereof, the spool being in the flat or "knocked down" condition, in this respect corresponding to Fig. 2.

Fig. 9 is a top view of the completed spool as set up for use.

Fig. 10 is a view similar to Fig. 9 but before the four side extensions have been folded inwardly, illustrating an intermediate step in setting up the spool. (The view is to a smaller scale than Fig. 9.)

Figs. 11 and 12 are transverse sectional views taken as indicated at 11—11 and 12—12 respectively in Fig. 9. In Fig. 11 one of the side extensions is shown partly folded to illustrate the final setting-up operation. Hence this view is illustrative of a condition intermediate those shown in Figs. 9 and 10.

2

Fig. 13 is a longitudinal sectional view taken as indicated at 13—13 in Fig. 9.

Referring first to Figs. 1 to 6 inclusive, my invention comprises in its general arrangement a folding spool having a body panel 14, extensions 15 at each side of the body panel and extensions 16 at each end of the body panel, outer end pieces 17 adjoining the end extensions and attached to the ends of the body panel 14 by means of said end extensions, inner end pieces 18 adjoining the ends of the side extensions 15 and having locking projections 19 at their ends.

The outer end pieces 17 are folded over against the end extensions 16 and secured thereto by suitable means, such as the metal staples 20 (Fig. 2), and the locking projections 19 are folded over and secured as by means of the staples 21.

In my preferred construction the inwardly folding side extensions 15 have inner sections 22 arranged to fold at right angles to the body panel, the outer sections of the side extensions 15 being arranged to fold into parallel spaced relationship to the body panel 14 as shown in Fig. 4. This construction provides a hollow rectangular shank for the spool so that it can be mounted on a spindle for winding. For this purpose the end pieces 17 have openings 23 through which the spindle passes. They may also have one or more openings 24 to receive lugs associated with the drive mechanism of a winding machine.

Also in my preferred construction portions of the side extensions 15 adjacent the inner end pieces 18 are cut out as at 25 to form projections 26 on the inner end pieces. When the spool is set up as shown in Figs. 3 to 5 inclusive, these projections 26 space the side extensions 15 from the body panel 14, the lower edges of the projections as viewed in Fig. 4 being brought into abutting relationship to the body panel. The adjacent locking projections 19 enter recesses 27 (Fig. 5) at the ends of the body panel. In the construction illustrated, recesses 27 are provided between the outer end pieces 17 and end extensions 16 between the staples 20 (cf. Figs. 4, 5 and 6). Score lines 28 between side extensions 15 and inner end pieces 18 preferably are offset slightly to the inside of score lines 29 between the body panel 14 and end extensions 16 so as to allow for the extra thickness of locking projections 19 when the spool is set up as will be understood from Figs. 5 and 6. However, if desired, the locking projections 19 can be omitted, in which case score lines 28 are not necessarily offset with respect to score lines 29.

and inner end pieces 18 are secured, as by metal staples, to outer end pieces 17.

The spool is formed from a single section of paperboard by cutting a blank of the form shown in Fig. 1. The U-shaped cut lines 25 to form projections 26 are made as shown in this view and the blank is scored or otherwise prepared for folding along the lines which define edges of the body panel, extensions, locking projections, and end pieces. Since the locking projections 19 and outer end pieces 17 are to be folded a full 180° about lines 30 and 31, I prefer to cut these lines quite deeply into the paperboard stock to facilitate making clean sharp-edged folds. The remaining fold lines 28, 29, 32, 33 may be formed as ordinary scores depressing the paperboard stock from the upper side as viewed in Fig. 1 so as to form grooves on what is to be the inside of the folds.

Formation of the spool in its knocked down form is accomplished by folding the locking projections 19 and outer end pieces 17 upwardly, inwardly and downwardly through an angle of 180° and stapling them to the inner end pieces 18 and end extensions 16 respectively as shown in Fig. 2. This is the completed spool ready for shipment. The spool is set up for use by lifting the inner edges of outer end pieces 17 until the latter are at approximately right angles to the body panel 14 and likewise lifting the inner edges of the locking projections 19 until they are at approximately right angles to the side extensions 15. Then the side extensions are folded inwardly about the score lines 32 and 33 so that the locking projections 19 come inside of the outer end pieces 17 with the ends of the locking projections sliding into the recesses 27 at the ends of the body panel and with the edges of the spacing projections 26 resting against the ends of the body panel. This is the completed spool ready for use.

If desired, the outer end pieces 17 can be formed with extending locking flaps 17^a (Figs. 3 and 5) which are arranged to fold over the inner end pieces 18. Projections 17^b formed on these locking flaps have interlocking engagement with recesses 25^a in the inwardly folding side extensions 15. Recesses 25^a are conveniently formed as notches at the edges of cut-outs 25 previously described. With this modification, the final step in setting up the spool for use is to fold locking flaps 17^a over the inner end pieces 18 as indicated by the arrows in Fig. 5, projections 17^b snapping into recesses 25^a to hold the flaps snugly against the inner end pieces.

Reference will now be had to Figs. 7 to 13 inclusive illustrating a modified construction embodying my invention. The general arrangement is the same as in the embodiment previously described, the spool comprising a body panel 34, extensions 35 at each side of the body panel and extensions 36 at each end of the body panel, outer end pieces 37 adjoining the end extensions 36 and attached to the ends of the body panel 34 by means of said end extensions, inner end pieces 38 adjoining the ends of the side extensions 35 and having locking projections 39.

The outer end pieces 37 are folded over against the end extensions 36 and secured thereto by suitable means, such as by metal staples or an adhesive; for example, glue may be applied over the surface of the end extensions 36 and/or the adjacent section of the end pieces 37 before the latter are folded over against the extensions.

The inwardly folding side extensions 35 have

inner sections 40 arranged to fold at right angles to the body panel, the outer sections of the side extensions 35 being arranged to fold into parallel spaced relationship to the body panel 34 as shown

in Fig. 12. Portions of the side extensions 35 adjacent the inner end pieces 38 are cut out as at 41 to form the locking projections 39 on the inner end pieces 38, heretofore referred to. These locking projections preferably are formed with shoulders 42 so that when the spool is set up, the shoulders 42 will be brought into abutting relationship to the body panel, and so that the portion of each projection 39 which lies between its shoulders 42 and the inner end pieces 38 will serve to space the side extensions 35 from the body panel as shown in Figs. 11 and 12. Openings 43 are cut in the end extensions 36 and extend for a short distance into the body panel to form recesses 44 at the ends of the body panel. The locking parts 39 of the projections enter these recesses 44 and lie within the openings 43 in the plane of the end extensions 36 (cf. Figs. 12 and 13). Openings 43 may be shouldered as at 45 for locking engagement with a cut out portion 46 of the projections 39 to hold the spool firmly in its final set up condition. Openings 43 preferably are wider than the locking parts of the projections 39 to permit the latter to pass by the ends of the shoulders 45 when setting up the spool.

As in the case of the embodiment previously described, the spool is formed from a single section of paperboard by cutting a blank of the form shown in Fig. 7. The cut lines and scores likewise may be made as previously described except that in this modification there are also cut lines at 47 separating the end extensions 36 from the inner end pieces 38.

Formation of the spool in its knocked down form is accomplished by folding the outer end pieces 37 upwardly, inwardly and downwardly through an angle of 180° and gluing or stapling them to the end extensions 36 as shown in Fig. 8. This is the completed spool ready for shipment. The spool is set up for use by lifting the inner edges of outer end pieces 37 until the latter are at approximately right angles to the body panel 34 and depressing the outer edges of the inner end pieces 38 until they are at approximately right angles to the side extensions 35. The spool will then be in the form shown in Fig. 10. Next the side extensions are folded inwardly in the manner indicated in Fig. 11. The side extension at the left end of this view is in its final position and that at the right hand is in an intermediate position. After the spacing and locking projections 39 have been brought into the position shown in Fig. 12 the spool will be completed and ready for use.

The terms and expressions which I have employed are used in a descriptive and not a limited sense, and I have no intention of excluding such equivalents of the invention described, or of portions thereof, as fall within the purview of the claims.

I claim:

1. A folding spool comprising a body panel, end pieces attached to the ends of the body panel, inwardly folding extensions at each side of the body panel, and locking projections at the ends of said extensions; said locking projections entering recesses at the ends of the body panel when the extensions of the body panel are folded inwardly to hold the end pieces at substantially right angles to the body panel.

2. A folding spool formed from a single section of paperboard and comprising a body panel, extensions at each side and each end of the body panel, outer end pieces adjoining the end extensions, said outer end pieces being folded over against the end extensions and secured thereto, and inner end pieces adjoining the ends of the side extensions, said inner end pieces having locking projections folded over and secured, and the side extensions folding inwardly between said outer end pieces to hold the latter at substantially right angles to the body panel.

3. A folding spool formed from a single section of paperboard and comprising a body panel, extensions at each side and each end of the body panel, outer end pieces adjoining the end extensions, said outer end pieces being folded over against the end extensions and secured thereto, and inner end pieces adjoining the ends of the side extensions, said inner end pieces having locking projections folded over and secured, and the side extensions folding inwardly between said outer end pieces to hold the latter at substantially right angles to the body panel, the locking projections entering recesses formed at the ends of the body panel.

4. A folding spool as defined in claim 1, in which each of the inwardly folding extensions has inner and outer sections, the inner section arranged to fold at right angles to the body panel and the outer section arranged to fold into parallel spaced relationship to the body panel.

5. A folding spool as defined in claim 2, in which portions of the side extensions adjacent the inner end pieces are cut out to form projections of the inner end pieces which space the side extensions from the body panel when the side extensions are folded inwardly between the outer end pieces.

6. A folding spool formed from a single section of paperboard and comprising a body panel, extensions at each side and each end of the body panel, outer end pieces adjoining the end extensions, and inner end pieces adjoining the ends of the side extensions, said outer end pieces being folded over against the end extensions, and portions of the side extensions adjacent the inner end pieces being cut out to form projections of the inner end pieces which space the side extensions from the body panel when the side extensions are folded inwardly between the outer end pieces.

7. A folding spool comprising a body panel having inwardly folding extensions at each side thereof, outer end pieces attached to the ends of the body panel and inner end pieces attached to the ends of said extensions, the inner end pieces fitting within the outer end pieces to hold the latter at substantially right angles to the body panel, and locking flaps extending from the outer end pieces arranged to fold over the inner end pieces.

8. A folding spool comprising a body panel having inwardly folding extensions at each side thereof, outer end pieces attached to the ends of the body panel and inner end pieces attached to the ends of said extensions, the inner end pieces fitting within the outer end pieces to hold the latter at substantially right angles to the body panel, and locking flaps extending from the outer end pieces arranged to fold over the inner end pieces, said locking flaps having projections for interlocking engagement with said inwardly folding extensions.

9. A folding spool as defined in claim 6, in which part of said projections enter recesses formed at the ends of the body panel.

10. A folding spool formed from a single section of paperboard and comprising a body panel, extensions at each side and each end of the body panel, and end pieces adjoining the end extensions, said end pieces being folded over against the end extensions and secured thereto, the side extensions folding inwardly between said end pieces to hold the latter at substantially right angles to the body panel, the side extensions having locking projections at their ends, and the ends of the body panel having cut-out portions to receive said locking projections.

ARTHUR J. WEISS.
